UNITED STATES PATENT OFFICE

PETER L. HOFFMAN, OF AURORA, ILLINOIS, ASSIGNOR TO RICHARDS-WILCOX MANUFACTURING COMPANY, OF AURORA, ILLINOIS, A CORPORATION OF ILLINOIS

SUPPORTING DEVICE FOR OVERHEAD TRACKS

Application filed February 21, 1927. Serial No. 169,791.

My invention relates to devices for supporting door hanger and similar overhead tracks, and particularly tracks of inverted U-shape, such as are commonly used as runways for trolleys from which sliding doors are suspended. Track of such design is usually made in sections of convenient length, and a plurality of these sections are mounted with their adjoining ends abutting, so as to make up a continuous track of the required total length. It is therefore important to hold the several sections against endwise movement that would open up spaces at the joints, as the opening of such gaps would obviously interfere with the smooth running of the trolleys or door hangers, and would cause jolts that would tend to loosen the track supports as well as to jar the door and the hangers, resulting in their more rapid deterioration. The object of my present invention is to provide improved means for supporting a track made up of a plurality of sections, by which the several sections will be firmly supported, and also will be held against endwise movement relatively to each other; also to provide supporting means of this character that will be of simple and inexpensive design. I accomplish this object as illustrated in the drawings, and as hereinafter described. What I regard as new will be set forth in the claims.

In the drawings, Fig. 1 is a perspective view of parts of two adjoining track sections of inverted U-shape, supported and connected by my improved supporting means.

Fig. 2 is a longitudinal vertical section on line 2—2 of Fig. 3.

Fig. 3 is a vertical cross section on line 3—3 of Fig. 2.

Fig. 4 is a perspective view of the yoke member that constitutes a part of the connecting means, and Fig. 5 is a longitudinal vertical section showing a modification.

Referring to the drawings 6, 7 indicate two track sections of like cross sectional contour,

which in the illustrations is somewhat like an inverted U, although, as best shown in Figs. 1 and 3, inwardly extending flanges 8 are provided at the lower side margins of the sections, said flanges being spaced apart, as shown at 9, to form a slot for the passage of the rod or other part of the trolley or hanger to which the door or other load is attached. Said flanges are preferably provided with upturned lips, forming channels at either side of the slot 9, in which the trolley wheels travel, but it should be understood that such lips are not essential, and that the contour of the track sections may also be modified in other respects.

As has been suggested, in installing the track, the sections thereof are aligned, with the proximate ends of adjoining sections abutting against each other, so as to make a continuous runway. The track is supported opposite such joints by a two-part bracket comprising an inner member or plate 11, which for the most part is flat, as shown in Fig. 3, but is provided at its lower end with an out-turned flange or lip 12 that extends under the inner flange or channel of the track sections, the inner wall of such sections bearing against the flat surface of said plate, which extends upward some distance above the track sections, for conveniently attaching it to a wall or other support, as by a bolt 13.

The track supporting bracket also comprises an outer member 14, which is approximately Z-shaped, as it has a vertical portion 15, that fits against the upper portion of the plate 11; a horizontal intermediate portion 16, that extends over the upper surface of the track sections; and a vertical portion that bears against the outer vertical face of the track sections and overlies the joint between them. At the lower end of the portion 17 is an inturned flange 18, that extends under the outer flange 8 of the track sections, which therefore rest upon and are supported by the flanges 12, 18, as shown in Fig. 3. The mem-

ber 14 is so proportioned that the horizontal portion 16 thereof lies a short distance above the upper surface of the track sections, as shown in Figs. 2 and 3, and the upper portion 15 is firmly secured to the plate 11 by the bolt 13, which passes through aligned holes in both, and also by offset tongues 19 struck up from the plate 11 into slots or notches 19' formed in the part 15 at opposite sides of the bolt 13. Thus the two members of the bracket are firmly connected together when the bracket is secured in place by the bolt 13.

The track sections are mounted in the bracket so that the joint at their meeting ends 15 lies preferably midway between the end margins of the bracket, and said sections are secured together and to the bracket by means of a U-shaped yoke 20, comprising a substantially flat intermediate portion 21 and down-turned end portions 22 provided with tongues 23 and shoulders 24 at opposite sides of said tongues, as best shown in Fig. 4. The yoke 20 is of such length that it is adapted to embrace the bracket members 14 at its horizontal portion 16, with the shoulders 24 bearing on the upper surface of the track sections, and the tongues 23 projecting into slots 25 formed in said track sections, as best shown in Figs. 2 and 3. A bolt 26 secures the yoke to the 20 horizontal portion 16, the head 27 of said bolt bearing against the under surface of said portion 16, while a nut 28 is screwed on the upwardly extending shank of the bolt, which passes through suitable holes in the bracket 35 member and yoke.

Manifestly the bolt 26 holds the yoke firmly in place on the bracket member 14, and the yoke holds the track sections against endwise movement tending to open up the joint. By 40 removing the nut 28 the yoke may be detached to permit the track sections to be demounted.

In Fig. 5 I have shown a modified arrangement in which instead of employing tongues 45 formed on the yoke, I provide upturned lips 29 struck up from the upper portions of the track sections 6, 7, at such points that they abut against the inner faces of the down-turned portions 22^a of the yoke, and so prevent endwise movement of the track sections. This form is substantially a reversal of that shown in the other figures. In both forms the yoke holds the track sections down firmly on the flanges 12, 18, and in both it forms an 55 interlocking connection between the bracket and the track sections that holds the latter against endwise movement with respect to the bracket, or to each other, and yet permits them to be easily assembled or disconnected. So 60 far as this feature of my invention is concerned, it may be used in connection with a single piece bracket, although the two piece bracket is a more advantageous construction.

What I claim as my invention and desire 65 to secure by Letters Patent, is—

1. The combination of an overhead track, and means for supporting it in place, said means comprising a bracket extending over and partially beneath the track, a yoke extending over and secured to the bracket above the track and having down-turned ends provided with tongues projecting into slots in the track, and a bolt securing the yoke to the bracket. 70

2. The combination of an overhead track, and means for supporting it in place, said means comprising a bracket extending over and partially beneath the track, a yoke extending over and secured to the bracket above the track and having downturned ends provided with tongues projecting into slots in the track, and a shoulder bearing on the track, and a bolt securing the yoke to the bracket. 75 80

3. In combination, an overhead track, a separable two part bracket extending over and partially beneath the track, means for securing the bracket to a supporting structure and for releasably securing the two parts of the bracket together and holding them against relative movement, a yoke straddling the upper horizontal arm of the bracket and bearing on the top wall of the track, and means for detachably securing the yoke to the bracket and for forcing said yoke toward the track, the yoke and the track having co-operating means holding the track against endwise movement with respect to the bracket. 95

4. The combination of an overhead track comprising a number of sections, and means for supporting the track in place, said means comprising a bracket extending over and partially underneath the track, a member on the bracket extending longitudinally of the track and adapted to bridge a pair of abutting track section ends in the bracket and having means adapted to be forcibly urged into engagement with the track, and means to fasten said member to the bracket. 100

5. The combination of an overhead track, and means for supporting it in place, said means comprising a bracket extending over and partially beneath the track, a yoke embracing a portion of the bracket above the track and having projections near the ends thereof, said track having means cooperating with said projections to prevent endwise movement of the track in the bracket, and means securing the yoke to the bracket. 110 115

6. The combination of an overhead track, and means for supporting it in place, said means comprising a bracket extending over and partially beneath the track, a yoke secured to the bracket above the track and having means near the ends thereof adapted to project into openings in the track, and means securing the yoke to the bracket and adapted to press the same against the track. 120 125

7. In combination, an overhead track comprising a plurality of sections arranged end 130

to end, a bracket extending about and partially beneath the adjacent end portions of two successive track sections, a securing and pressure applying member bridging said adjacent end portions of the track sections, said member and the track sections having cooperating means for securing the track sections together and for exerting pressure upon the track sections, and means for securing said member to the bracket and for exerting downward pressure upon the securing and pressure applying member and upward pressure upon the bracket.
